RECORD REVERSING MECHANISM

Francis John Offen, Swindon, England, assignor
to Garrard Engineering & Manufacturing
Company, Limited, Swindon, England, a cor-
poration of Great Britain

Application August 27, 1942, Serial No. 456,442

5 Claims. (Cl. 274—10)

This invention relates generally to automatic phonographs and similar machines for reproducing sound recorded on disc records, in which a plurality of records assembled in a magazine above the turntable of the machine are successively delivered thereto, and is more particularly directed to a mechanism for reversing the position of a record upon the turntable after the recording on one face thereof has been rendered, for the reproduction of the recording on the opposite surface thereof and for subsequently removing the record from the turntable for deposit in a suitable storage receptacle.

In United States Letters Patent No. 2,297,014, granted September 29, 1942, on my co-pending application for Letters Patent, Serial No. 392,200, filed May 7, 1941, for "Magazine phonographs," of which this application is a continuation in part, I have illustrated and described a series of co-related and co-acting mechanisms for automatically reproducing recordings from a plurality of pre-selected disc records, initially stacked above the turntable of the phonograph, in which co-acting mechanisms function for successively delivering the records to the turntable, together with mechanism actuatable from the motor of the machine, in appropriately timed relation to the record delivery and reproducing mechanisms, for operating a record-engaging arm which, in sequence, raises a record that has just been reproduced from its position upon the turntable to transfer it to another position, effect a reversal of the record and again deliver it to a position for deposit upon the turntable, for the reproduction of the second recording carried thereby.

Specifically, this application is directed to the mechanism described in my aforesaid co-pending application, for reversing the position of a record upon the turntable, after the recording on one surface has been reproduced, for the reproduction of that on the opposite surface of the record and for subsequently removing the record from the turntable and transferring it to a storage receptacle, together with certain modifications of such structure, which may be employed in lieu of that shown in my said application, as may be desired or dictated by construction and operation requirements.

The general object of this invention, therefore, is to provide a disc record turning or reversing mechanism, as aforesaid, which will be of a simplified and practical design and most efficient in operation, the means whereby the records are engaged for lifting from the turntable and retained in engaged position during the reversal and re-

transfer of the record to position for deposit on the turntable, insuring positive support and engagement of the record throughout the cycle of operations thereof.

5 It is also an important object of this invention to provide a record reversing mechanism, as aforesaid, which will efficiently function in conjunction with records of so-termed mixed sizes, as, for example, records of 10" and 12" diameter, intermixed in any preferred arrangement in the initial stacking of the records for subsequent reproduction.

10 Other objects and advantages flowing from the practicing of my invention will become apparent as the detail description of the preferred embodiments thereof, shown in the accompanying drawings, proceeds.

In the drawings:

Figure 1 is a top plan view of an automatic sound reproducing mechanism, as shown in my co-pending application, in which my present invention is incorporated, the record-engaging arm thereof, being shown in the position which it assumes for the reversal of the record or for depositing it in the storage receptacle, as the case may be.

20 Figure 2 is a plan view, similar to Figure 1, in which the record-engaging arm is shown in dotted lines beneath a record poised above the turntable.

25 Figure 3 is a side elevation of the phonograph mechanism, disclosing the cam mechanism which functions in the operation of the tone arm, record magazine and record reversing arm.

30 Figure 4 is an enlarged view of a detail of the actuating mechanism shown in the preceding figure.

35 Figure 5 is a view in perspective, partly in section, of the record reversing arm and its actuating mechanism.

40 Figure 6 is a cross-sectional view of one of the cams of the latter mechanism, on the line 6—6 of Figure 5.

45 Figure 7 is an enlarged bottom plan view of the record reversing arm, as shown in Figure 5, illustrating the record-gripping members thereof.

Figure 8 is a sectional elevation of a modified record-reversing arm assembly, the outer end of the arm being broken off, and

Figure 9 is a plan view of the underside of the record supporting and gripping end of the broken arm shown in the preceding figure.

55 Referring now to the drawings in detail, in which like characters of reference are employed to designate similar parts in the several views,

the phonograph, as shown in Figures 1, 2, and 3, comprises a pick-up arm 30 mounted above the motor-board 32, for movement across the turntable 33, provided with the usual pin (not shown) for centering the records thereon. The records are initially stacked in a magazine composed of a plurality of spaced vanes 36, the records being maintained concentric to the turntable by a vertically adjustable rod dependent from the arm 40 which is suitably supported from the motor-board, the upper end of the rod embodying a knob 41 whereby the rod may be raised to facilitate the stacking of the records in the magazine.

A feeler arm 51 is rotatably mounted for its roller 52 to engage the edge of a record positioned upon the turntable to detect the size of such record, a suitably mounted shut-down arm 53 being adapted for engagement by the edge of the lowermost record in the magazine for controlling the functioning of the motor switches, appropriate knobs 54, 55, 56 and 57 being provided on said motor-board for selectively operating the phonograph.

The system of cams for operating the various mechanisms, including that for actuating the record-reversing arm, is shown in Figures 3 and 4, the shaft 60 being driven by the record-changing motor (not shown) through reduction gearing indicated at 61, which, in turn, drives pinion 62 in mesh with the gear 63, secured to said shaft 60. The other end of the latter shaft is provided with a small gear 64 driving pinion 65 keyed to the stub shaft 66. A series of cams, collectively indicated at 67, are mounted on said stub shaft 66 which operate pick-up arm 30, the feeler arm 51 and suitable switch mechanism (not shown).

As long as the motor functions, it will drive the cams 67 through the aforesaid gears 62, 63, 64 and 65. Cam sleeve 68 embraces the shaft 60 and is adapted to be coupled thereto by the clutch 265, the cam group, indicated at 70, secured to the cam sleeve 68, serving to control the movements of the record changing mechanism, including the record-reversing arm 42. The ratio of gears 62, 63, 64 and 65 provides for two revolutions of the cams of group 67 per cycle, while the cams in group 70 revolve but once in each cycle.

The aforesaid record reversing arm 42 is rotatably mounted in a sleeve 43 carried by the casing 44 mounted for horizontal rotation on the aforesaid motor-board 32, as and in the manner hereinafter described. Elevators 47 and 48 are reciprocably mounted on said motor-board for functioning in the delivery of a record to the turntable from the magazine, and are adapted to cooperate with said record reversing arm for permitting the latter to engage a record for reversal and redeposit upon the turntable, as will become apparent, a record-supporting arm 50 being mounted to swing into position at a predetermined point in the delivery of a record to the turntable, to cooperate with the vanes 36 in supporting the remaining stacked records.

Upon the completion of the reproduction of the recording on one surface of a record, the elevators 47 and 48 rise to lift the record from the turntable and permit the arm 42 to swing beneath the record, as shown in dotted lines in Figure 2, the elevators then receding to impose the record upon said arm, in engagement with the lateral end extensions 45 and cooperating offset 45a, which provide a three-point support for the record beyond the central zone thereof. The functioning of the record-gripping mechanism 46 now effects a rigid interengagement of the arm with the

record, through the medium of an expandable pin which is entered in the center aperture of the record when deposited on said arm, the oppositely actuatable sections of the pin being indicated at 141 and 142. The arm is then swung to a position above the receptacle 113 and rotated on its axis 180 degrees to reverse the position of the record from that which it had previously assumed upon the turntable, the arm then returning to its position above the turntable. The record which is now supported from the underside of the arm, in engagement with said expandable pin, is then released by the contraction of said pin, to drop to the turntable, in position upon the pin 34 thereof, the elevators 47 and 48 remaining in their lowermost position.

The record reversing arm 42 remains above the turntable during the functioning of the pick-up arm upon the surface presented thereto by the reversal of the record, as just described, and when the reproduction is completed, the elevators again rise to lift the record to a position immediately below said arm for the entry of the expandable pin in expanding engagement with the center hole thereof, the arm then swinging outwardly over the receptacle 113 for the release of the record thereinto, upon the contraction of said pin, the record delivery mechanism functioning to effect the delivery of another record to the turntable, to repeat the cycle of operations.

In the structure shown in Figures 5 and 7, the arm 42 rotates 180 degrees about its axis within the sleeve 43 in the reversal of the record carried thereby. This rotative movement is imparted to the arm by the rack 116 secured to the upper end of the vertical pull rod 117 in mesh with the pinion 115, fixed to the inner end of said arm 42 within the casing 44, the rack being reciprocated to effect a complete turnover of said arm 42 in one movement of the rack and to rotate the arm back to its initial position in the opposite movement thereof. The vertical movement of pull rod 117 is obtained through a further rack and pinion. A rack 118 embraces sleeve 120, and is slidable thereon. Rack 118 meshes with pinion 121 secured to shaft 122. Rack 118 bears plate 123 on which pull-rod 117 is fixedly mounted. Spring 125 bears against a shoulder on pull-rod 117, and against plate 123.

The oscillating movement of the record reversing arm 42 is derived by a corresponding rotary movement of the casing 44 and the sleeve 43. For this purpose casing 44 has a depending sleeve 120. A pinion 131 secured to sleeve 120 meshes with a rack 132. The reciprocatory movement of rack 132 is secured by crank lever 133 attached to shaft 134. Crank lever 135 is secured to shaft 134, and engages with cam groove 136 of cam 137. Cam 137 is also secured to cam sleeve 68 and rotates in unison with cam 130. Figure 6 is a detail cross-sectional view through cam 137. Crank lever 133 is not rigidly connected with rack 120, but is slidable thereon. The rocking movement of crank lever 133 is transmitted to rack 132 by springs 138 and 140, to insure a smooth oscillating movement by record reversing arm 42. It will now be evident that rotation of cam 137 rocks crank lever 133, which in turn rocks crank lever 135. Rack 132 is thus displaced to the left or to the right, which in turn causes a corresponding rotation of casing 44.

Each record is adapted to be gripped by levers 46 having integrally formed segmental protuberances adjacent their free ends adapted to coat to engage with the central hole of a record, as

shown in detail in Figure 7. Segmental protuberances 141, 142 are disposed centrally on the outer end of record reversing arm 42, and project therefrom and are movable towards and away from each other, in the contraction and expansion action of the levers 46. The levers 46 are pivotally mounted on record reversing arm 42 at 145. Spring 148 embraces the outer ends of the levers 46 tending to pull them together.

When tapered end 147 of sliding shaft 148 is displaced to the right, segmental portions 141, 142 are forced apart as seen in Figure 7. When sliding shaft 148 is moved to the left, spring 148 pulls segmental portions 141, 142 together for the record releasing position. The rear end of sliding shaft 148 has a head 150 which engages with bell crank lever 151. Bell crank 151 is operated by the upper end of a vertically slidable pull rod 152 which reciprocates within vertical sleeve 120. Slidable pull rod 152 is operated by crank 153 secured to one end of shaft 154. The other end of shaft 154 bears another crank 155 which is engaged by projection 156 on lever 157 pivoted intermediate its length at 158. The free end of lever 157 is engaged by projections 160 on cam 161 secured to cam sleeve 68.

When cam 161 rotates in unison with cams 130 and 137, its projections 160 rock lever 157 in a clockwise direction. The rocking movement of lever 157 causes rotation of shaft 154 in a counter-clockwise direction, which in turn lifts pull rod 152 through crank 153. When pull rod 152 moves upwards, its rocks bell crank lever 151, causing a movement of sliding shaft 148 supported on the underside of the arm 42, (see Figure 7) towards the left. The movement of sliding shaft 148 in the opposite direction is obtained by a spring, 148a surrounding the shaft 148 and interposed between the stop 148b, rigid therewith, and a fixed part of the sleeve 43.

In the modified construction of Figures 8 and 9, the underside of the arm 42 is grooved to form a guideway 2 for a rod 3 carrying lugs 4 and 5, spaced longitudinally thereof, adjacent its outer end, for actuating the jaw members 6 and 7, pivoted within the head 8, as at 9 and 10. Each of these jaw members carries a segment of what may be termed an expandable pin, corresponding to the pin of the structure of Figures 5 and 7, the pin segments being indicated by the reference numerals 11 and 12, the head of the arm embodying lateral projections 45 and a cooperating offset 45a for supporting a record in engagement with the aforesaid expandable pin. At its inner end, the rod 3 is offset for connection to the plunger 13, for conjoint linear movement, said plunger being concentric with and extending through the bearing end 42a of said arm 42, whereby said rod may be reciprocated to expand and contract said record-engaging pin segments, as hereinafter described.

The bearing end 42a of said arm 42 is mounted in suitable ball bearings 42b for rotation within the sleeve 44a, mounted in the laterally projecting sleeve 43 of the casing 44 which is superimposed upon the motor-board 32 for relative rotative movement on the ball bearings 42b, the rotative movement being imparted thereto by the actuation of the rack 132 in engagement with the pinion 131, fixed to the sleeve 14 rigidly connected to said casing 44 at its upper end, similarly to the construction of Figures 5 and 7, suitable ball bearings 15 being interposed between said pinion 131 and the lower cylindrical portion 16 of the underhousing 17 of the assembly.

A push rod 18, corresponding to the rod 152 of the structure of Figures 5 and 7, is similarly actuatable by the cam 153, the upward movement of the rod 18, in engagement, at its upper end, with the cam lever 19, pivotally mounted in the bearing 20, and abutting upon the inner end of said plunger 13, tending to rock said cam lever to urge said rod 3 in the direction of the head of the arm 42, in opposition to the spring 21, to cause said lug 4 to traverse the opposed inclined jaw surfaces with which it is engaged. The resultant spreading of the jaws inwardly of their pivots, produces a counter directional movement of the outer ends thereof, to mate the opposed surfaces of the pin-forming segments 11 and 12. Conversely, the downward movement of said push rod 18, permits the rod 3 to move in the opposite direction, under the influence of said spring 21 in engagement with the end wall of the recess 42c of the arm 42 and the lug 3a fast to the rod 3, the cam lever 19 following the push rod in its downward movement, in engagement with the inner end of said plunger 18. This reverse movement of the rod 3, as will be evident, will produce a spreading of the forward ends of the jaws 6 and 7, as their opposed chamfered surfaces are engaged by the lug 5, to expand the pin-forming segments 11 and 12 into engagement with the center aperture of a record, the lug 4 becoming ineffective upon the inner ends of said jaws, as will be obvious. The spring 21 is effective at all times, to maintain said cam lever 19 in engagement with both said push rod and said plunger, to eliminate lost motion in their conjoint movement.

At its inner end, the bearing portion 42a of the arm 42 is provided with a ring gear 22, or otherwise suitably formed with teeth, to mesh with the rack 115 on the upper end of the pull rod 117, the said plunger 13 being reciprocable through said gear, in engagement with the rockable cam lever 19, as described.

The pull rod 117 corresponds to its counterpart in the structure of Figures 5 and 7, and is likewise reciprocated in the rotative movement of the pinion 121 in engagement with the rack 118 to which said pull rod is connected for conjoint movement, as already described.

The operation of the record reversing arm 42 of the modified construction just described, corresponds to that of the record turning arm of Figures 5 and 7, as will be manifest, the arm moving into position beneath the elevator raised record, in response to the actuation of the pinion 131 in engagement with the rack 132, for the expansion of the pin segments into frictional engagement with the center aperture thereof, as the rod 3 is actuated by the spring 21. The arm then swings to a position above the receptacle 113, in a reverse movement of the rack 132, following the retraction of the elevators from their record-supporting position. The cam actuation of the pull rod 117 is now effective upon the rack-engaged pinion 115, to rotate the arm on its longitudinal axis 180 degrees to reverse the position of the record, the arm being then returned to its position above the turntable by the reverse directional movement of the rack 132 in mesh with the pinion 131, for the release of the inverted record from the underside of the arm to the turntable, as the pin segments 11 and 12 are contracted out of engagement with the orifice of the record, by the push rod actuation of the cam lever 19, in engagement with the plunger 13.

The arm remains in position above the turn-

table following the release of the inverted record, until the reproduction of the record is completed, when the record is again elevated into engagement with the arm poised thereabove for the expansion of the pin segments in engagement with the record aperture, the arm, in timed relation to the retraction of the elevators, again swinging to its position above the receptacle 113 as the rack 132 becomes effective to rotate the pinion 131 for actuating the arm to the latter position, the push rod then functioning to impel the rod 8 in the direction of the head of the arm to effect the disengagement of the pin segments from the record, to permit the record to drop into said receptacle. Following the discharge of the record into the receptacle, the arm is again rotated on its longitudinal axis, in a reverse directional movement of the pull rod 117 and its rack 116 in engagement with the pinion 115, to locate the pin-forming segments in position for entry in engagement with the central aperture of an elevated record, when lowered into engagement with said arm, when the arm is again returned to its record receiving position above the turntable.

While, for the purposes of this disclosure, I have described the record reversing arm and actuating mechanism, as incorporated in a phonograph of the type shown in my co-pending application, it will be understood that the present invention may be employed in conjunction with other record delivery mechanisms and such means as may be preferred for operating the pick-up arm, with appropriate mechanism for functioning the record-reversing arm, as herein described, in co-relation to the operation of such record delivery and reproducing mechanisms. Also, changes in details of the structure set forth, may be effected to meet different production and installation requirements, within the scope of the present invention, as defined by the appended claims.

I claim:

1. Mechanism for reversing a disc record, in the operation of a phonograph embodying a turntable and means for lifting a record from the turntable, to admit of the reproduction of the recordings on both surfaces of a record, said mechanism comprising a record carrying arm, a rotatably mounted support therefor, said arm being mounted on said support for rotative movement on its longitudinal axis relative to said support, mechanism for rotating said support to move said arm laterally in opposite directions, to alternately locate the free end of said arm above the turntable and in a second position remote from the turntable, record gripping means adjacent the outer end of said arm including a pair of levers pivotally mounted on said arm for opposite arcuate movement, each of said levers embodying a segmental protuberance at its outer end, said protuberances being adapted to enter the central aperture of a record for frictional engagement therewith to connect the record to said arm for movement therewith, lever-actuating means reciprocably mounted on said arm, means movable axially of said support operable when said arm is interposed between a lifted record and said turntable to become effective on said lever-actuating means to oppositely actuate said levers in a direction to expand said protuberances into frictional engagement with the record aperture to grip the record for the movement of said arm and the record superimposed thereon to the aforesaid second position, in response to the operation 75

of said support rotating mechanism, means operative on said arm when it comes to rest in the latter position for rotating said arm on its longitudinal axis to invert said arm and said record 5 engaged by said gripping means, whereby the record is dependently supported from said arm, said support rotating means sequentially operable to again move said arm to its position above the turntable and spring means effective for contracting said gripping means, for releasing the dependently supported record from said arm for redisposition on said turntable.

2. A mechanism for reversing disc phonographic records, including a record carrying arm, 15 a support therefor, said arm projecting laterally of said support and being connected thereto for rotative movement on its longitudinal axis, mechanism for oppositely rotating said support to dispose said arm above the turntable of a phonograph and in a position remote from such turntable, in alternating movements of said support, means adjacent the outer end of said arm for gripping a record to be carried thereby, said means including a pair of elements pivotally 20 mounted on said arm for opposite arcuate movement having projections adapted to enter the center aperture of a record, an actuator rod for positively concurrently actuating said elements in opposite directions and produce a separating 25 movement of said projections into expanding frictional engagement with the walls of a record aperture, spring means for urging said elements in the opposite direction to produce a contrasting movement of said projections out of engagement with such aperture to release a record, a push rod mounted for vertical reciprocation within said support, a pivotally connected member between said push rod and said actuator rod for positively actuating said latter rod in one direction, a pinion rigid with the inner end of said arm, a rack in mesh with said pinion, means for reciprocating said rack to oppositely rotate said arm on its longitudinal axis and a system of 30 cams for actuating said support rotating mechanism, controlling the movement of said elements and the concurrent like directional movement of said record gripping means into and out of effective position and actuating said rack for effecting the axial rotation of said arm in timed 35 relation to move said arm to position above the turntable beneath a record raised therefrom with said projections in uppermost position, grip the record, then move the arm to the aforesaid remote position, invert the record in engagement with said arm to a dependently supported position in the axial rotation of said arm, then return the arm and dependently supported record to position above the turntable to release the record thereto in the timed spring-actuated movement of the record gripping means to non-effective position, immobilizing the arm above the released record for reengaging actuation of the record gripping means therewith with said projections in dependent position, when the record is raised beneath said arm, again transferring the arm and the dependently supported record to said remote position and effecting the release of the record in a releasing movement of said record gripping means, for discharging the record from said arm and finally reversely rotating said arm on its longitudinal axis for again locating the record gripping means in uppermost position thereon, for the initiation of a corresponding cycle of operations of said record reversing mechanism.

3. In a record-changing mechanism for photographs playing central apertured records, an arm for gripping, moving and releasing records, means operably connected with one end of said arm for moving the same, record-gripping means mounted adjacent the other end of said arm and including a pair of levers, each pivotally mounted on said arm for radial and opposite movement, a segmental protuberance at the furthermost end of each lever, said protuberances being adapted to enter the central aperture of a record, a mechanism for actuating said levers respectively to displace the same in a direction to expand the protuberances into frictional engagement with the defining walls of the record aperture to grip the record and to displace said levers in a direction to contract said protuberances out of frictional engagement with said record to release the record, said mechanism including a reciprocating member movable between said levers and an associated spring chargeable by said reciprocating member in its displacement in one direction, means operable for longitudinally moving said reciprocating member to displace said levers in one direction with respect to the defining walls of the central aperture of the record and to charge the spring, said charged spring, upon withdrawal of the last-mentioned means, serving to reverse the directional movement of the reciprocating member and the directional displacement of the levers with respect to the defining walls of the record.

4. In a record-changing mechanism for photographs playing central apertured records, an arm for gripping, moving and releasing records, means operably connected with one end of said arm for moving the same, record-gripping means mounted adjacent the other end of said arm and including a pair of levers, each pivotally mounted on said arm for radial and opposite movement, said levers being disposed in parallelism, each having oppositely directed sets of bearing surfaces formed along their juxtaposed edges, a segmental protuberance at the furthermost end of each lever, said protuberances being adapted to enter the central aperture of a record, a mechanism for actuating said levers respectively to oppositely radially displace the same in a direction to expand the protuberances into frictional engagement with the defining walls of the record aperture to grip the record and to oppositely radially displace said levers in a direction to contract said protuberances out of frictional engagement with said record to release the record, said mechanism including a reciprocating member movable between said levers and an associated spring chargeable by said reciprocating member in its displacement in one direction, said reciprocating member having conformations to respectively cooperate with the one and the other

60

set of juxtaposed bearing surfaces on said levers, means for moving said reciprocating member in one direction whereby the respective levers are jointly displaced in one of the two directions relative to the defining walls of the central aperture of the record and the spring becomes charged, said spring, upon withdrawal of said last-named means, serving to displace the reciprocating member in the opposite direction, whereby the respective levers are jointly displaced in the reverse direction relative to the defining walls of the central aperture of the record.

5. In a record-changing mechanism for photographs playing central apertured records, an arm for gripping, moving and releasing records, means operably connected with one end of said arm for moving the same, record-gripping means mounted adjacent the other end of said arm and including a pair of levers, each pivotally mounted on said arm for radial and opposite movement, said levers being disposed in parallelism, each having oppositely directed sets of bearing surfaces formed along their juxtaposed edges, a segmental protuberance at the furthermost end of each lever, said protuberances being adapted to enter the central aperture of a record, a mechanism for actuating said levers respectively to oppositely radially displace the same in a direction to expand the protuberances into frictional engagement with the defining walls of the record aperture to grip the record and to oppositely radially displace said levers in a direction to contract said protuberances out of frictional engagement with said record to release the record, said mechanism including a reciprocating member movable between said levers and an associated spring chargeable by said reciprocating member in its displacement in one direction, a plurality of longitudinally spaced projections on said reciprocating member respectively cooperating with the one and the other set of juxtaposed bearing surfaces on said levers to radially displace the levers jointly about their respective pivotal mounting points, means for moving said reciprocating member in one direction whereby one of the projections thereon contacts with one of the sets of opposing bearing surfaces of the levers to radially displace the levers jointly in one of the two directions relative to the defining walls of the central aperture of the record and the spring being charged, said spring, upon operative withdrawal of said last-named means, serving to displace the reciprocating member in the opposite direction, whereby the other projection thereon contacts the other set of bearing surfaces of the lever to radially displace the levers jointly in the reverse direction relative to the defining walls of the central aperture of the record.

FRANCIS JOHN OFFEN.
